OIL BURNER

Monroe Brittain, Chickasha, Okla.

Application February 1, 1938, Serial No. 188,173

4 Claims. (Cl. 158—75)

This invention relates to oil burners, and more particularly to burners adaptable for fire boxes of locomotives or other fired apparatus.

The primary object of the invention is to improve generally upon oil burners of this character whereby to simplify the structure and minimize the cost of manufacture without detracting from the durability and efficiency of the device.

An important object of the invention is to secure a more thorough breaking up of the oil into relatively small particles and the atomization and commingling of the steam and air with the oil for perfect combustion.

With these and other objects as will herein-after more fully appear, the invention consists in the novel features of construction, combinations and arrangements of parts as hereinafter described and pointed out in the appended claims.

In the accompanying drawing illustrating a practical embodiment of the invention;

Figure 1 is a longitudinal vertical section through the burner; and

Figure 2 is a view of the oil breaking pan detached from the burner, it being severed from the burner substantially on the line 2—2 of Figure 1.

Referring now to the drawing, A designates generally the burner structure as a whole. As shown, the device includes an elongated horizontal tubular nozzle 10, the forward end portion of which is tapered, as at 11. Forwardly beyond the tapered portion 11 the nozzle is formed with a horizontal lip 12 having an up-standing side flange 13 on each side thereof, said flanged lip portion being of substantial width and open at its outer end.

The rear end portion of the nozzle tube 10 is externally screw-threaded to receive thereon a longitudinally adjustable cap member 14 having a central opening in which the end portion 15 of a steam jet tube 16 is tightly fitted. As shown, the end 15 of the steam jet is extended beyond the cap 14 and provided with a nipple 17 to the outer end of which a steam supply pipe 18 is attached. The forward end portion of the steam jet tube 16 is contracted, as at 19, to provide a restricted jet orifice 20.

As just above noted, the cap member 14 is adjustable longitudinally on the nozzle tube 10. Obviously, therefore, the steam jet tube 16 is accordingly adjustable longitudinally of said tube 10, whereby to vary the distance between the jet orifice 20 of said tube 16 and the restricted outlet opening 21 between the tapered portion 11 and the laterally flanged lip 12 of the nozzle tube

10. In addition to the longitudinal adjustment of the steam jet tube 16 a transverse adjustment of the discharge end portion of said tube is afforded by the provision of radial adjusting and supporting screws 22 provided therefor in the nozzle tube 10, by which provision the discharge orifice 20 of the steam jet tube 16 is obviously adjustable in any direction desired transversely of the restricted opening 21 of the nozzle tube 10.

Supported near one end, as at 23, on a nipple-like plug 24 extending upwardly from an opening provided therefor in the rear upper portion of the nozzle tube 10, is a tubular oil supply member 25 which extends forwardly parallel with the nozzle tube 10. The member 25 is provided at its rear end with an internally screw threaded inlet opening 26 for the attachment of an oil supply pipe (not shown). The forward end portion of the member 25 has an opening of substantially the same diameter as the bore of the tube 25 and it is externally screw threaded to receive a correspondingly internally screw threaded supporting extension 27 of an oil bowl 28.

The oil bowl 28 is provided with a cap or top closure member 29 which is preferably detachable and secured in place in any desired manner. The bottom of the bowl 28 is inclined upwardly and forwardly from its inner-side, as at 30, and it is provided with an opening 31 surrounded by an up-standing cylindrical discharge column 30 32 which is open at its upper end and terminates in proximity to the under-side of the cap or closure member 29. The upper end portion of the tubular discharge column 32 is provided with notches 33 at opposite sides through which oil 35 from the annular chamber surrounding the column 32 is permitted to flow into said column before reaching the level of the extreme end of the column.

An air inlet pipe 34 is inserted into the oil bowl 28 through the cap member 29 and is provided on its outer end with an apertured cap 35 through which heated air is taken into the pipe 34 as will be later more fully described. At the inner end of the pipe 34 is an elbow 36 to which is attached the end portion of a pipe section 37 extending axially through the tubular oil supply member 25 and having an elbow 38 at its opposite end which is connected to the nipple-like plug 24 by a short pipe extension 39 and whereby communication is provided directly with the interior of the nozzle tube 10 through the opening 40 in the plug 24.

In the operation of the burner the space between the bottom of the oil bowl and the flanged

lip portion 12 of the burner nozzle tube constitutes the combustion chamber into which a jet of steam is directed from the discharge orifice 20 of the jet tube 16, the effect of which is to draw heated air into the nozzle tube 10 from the connected supply pipes 34, 37 and 39, said air being drawn into the pipe 34 through the apertured cap 35 in a pre-heated condition owing to the location of said cap member 35 in close proximity to the oil bowl 28, which latter is obviously heated as a result of the combustion of the mixture of the atomized steam and air with the heated oil flowing into the combustion chamber from the oil bowl 28 through the discharge column 32.

In order to accomplish a more thorough breaking up of the oil and its proper proportionate mixture with the atomized steam and air, a perforated baffle in the form of a marginally flanged plate or pan 41 is provided between the bottom of the oil bowl 28 and lip extension 12 of the nozzle tube 10. As shown the bottom wall or plate of this baffle 41 is provided, near its inner end, with a series of relatively small apertures 42 arranged in transverse rows, and between these perforations and the outer end of the baffle are provided additional rows of apertures 43 and 44, respectively, of proportionately increased area.

The purpose of the perforated baffle 41, which is located directly in the zone of combustion and thereby becomes highly heated, is to break up the oil into small particles as it is discharged from the column 32 of the oil bowl 28, in which latter, obviously, the oil is pre-heated before overflowing into said column 32. Hence, by having the smaller opening 42 at the rear portion of the baffle 41, where the oil first strikes the plate, the oil is passed in relatively small particles into the combustion chamber in the region near and just above the restricted steam and air outlet 21, which thereby produces an effective combustible mixture of the steam, air and oil, which is particularly advantageous when the locomotive is standing or drifting and not using much oil, and yet when the locomotive is operating under conditions requiring a greater flow of the oil and the oil accordingly spreads upon the baffle in greater volume, it is delivered into the combustion chamber in increased size of its particles towards the outer end of the baffle and into the zone of increased combustion.

A burner construction and arrangement of the character herein illustrated and described is not only simple, compact and economically produced, but it is highly efficient in operation both under idling and low speed requirements and under increased load conditions and requires but little, if any, re-adjustment for given conditions.

While the structure herein illustrated embodies a practical adaptation of the invention it is understood that modifications and alterations may be made without departing from the spirit of the invention as defined in the appended claims. The invention, therefore, is not limited to the specific construction and arrangement shown in the accompanying drawing.

What is claimed is:

1. In an oil burner of the character described, a horizontal tubular nozzle member provided with a restricted discharge opening and a laterally flanged lip extension forward of the discharge opening, an axial steam jet member lo-

cated within said nozzle member with its discharge orifice in co-operative relation to the discharge opening of the nozzle, air inlet means at the rear portion of said nozzle member, an oil bowl over-hanging the lip extension of the nozzle member, said bowl having a forwardly and upwardly inclined bottom provided with an outlet opening, a tubular column surrounding the outlet opening of the oil bowl and terminating at its upper end adjacent to the top of the bowl, and a pan-like oil breaking element secured to the under-side of the oil bowl and interposed between the outlet opening of the bowl and the lip extension of the nozzle member, the bottom of said oil breaking element being provided with a plurality of apertures.

2. The oil burner structure as recited in claim 1 and in which the apertures in the oil breaking element are of increasing size from the inner end to the outer end of the element.

3. An oil burner comprising a substantially horizontal tubular nozzle member having a restricted outlet and a laterally flanged lip extension forward of said outlet, a steam jet tube extending axially through the nozzle member and terminating in a discharge end inwardly adjacent to the restricted outlet of said nozzle member, a horizontal tubular oil supply member supported on the nozzle member and extending longitudinally thereof, an oil bowl communicably attached to and supported on the end of said tubular oil supply member and overhanging the lip extension of said nozzle member, an air supply pipe extending into said oil bowl, thence axially through said oil supply member and into direct communication with the interior of the nozzle member, said oil bowl having a discharge opening in its bottom, an upstanding tubular column on the bottom of the bowl, surrounding said bottom opening and terminating near the top of the bowl, and an apertured baffle interposed between the discharge opening of the bowl and the lip extension of said nozzle member.

4. An oil burner comprising a substantially horizontal tubular nozzle member having a restricted outlet and a laterally flanged lip extension forward of said outlet, a steam jet tube extending axially through the nozzle member and terminating in a discharge end inwardly adjacent to the restricted outlet of said nozzle member, a horizontal tubular oil supply member supported on the nozzle member and extending longitudinally thereof, an oil bowl communicably attached to and supported on the end of said tubular oil supply member and overhanging the lip extension of said nozzle member, an air supply pipe extending into said oil bowl, thence axially through said oil supply member and into direct communication with the interior of the nozzle member, said oil bowl having a discharge opening in its bottom, an upstanding tubular column on the bottom of the bowl, surrounding said bottom opening and terminating near the top of the bowl, and an apertured baffle interposed between the discharge opening of the bowl and the lip extension of said nozzle member, said baffle comprising a pan-like member having a plurality of apertures in its bottom arranged in series of relatively small area near the inner end of the baffle and of increasing area in series progressively toward the outer end of the baffle.

MONROE BRITAIN,
